ELECTRON TUBE MOUNT INCLUDING TWO ELECTRODES SUPPORTED ON A COMMON INSULATING HEADER

Carl Theodore Johnson, New Providence, Pa., assignor to Radio Corporation of America, a corporation of Delaware

Filed Dec. 21, 1960, Ser. No. 77,399

8 Claims. (Cl. 313—260)

The present invention relates to an electron tube mount having a structure for facilitating the assembling of the parts thereof in a predetermined order, and to an advantageous method of assembling the parts referred to.

One type of electron tube includes a mount comprising a header of insulating material on which are mounted in concentric relation a directly heated cathode and a tubular grid having a plurality of side rods supporting a helix of lateral wire. The directly heated cathode may have a tubular structure constituted of a wire mesh, to the end portions of which are affixed metal rings or end plates for connecting the end portions aforementioned to suitable lead-ins.

Certain considerations involved in the aforementioned mount make it critical that the parts thereof be mounted in a desired order. One of the major considerations is related to the cathode. One type of tubular mesh cathode is composed of wires that have been conditioned suitably for emission, prior to the assembly thereof in the mount. Such conditioning may involve coating the wire with emitting material. The coating so produced is sensitive to relatively high temperatures prior to enclosure of the cathode in an evacuated envelope, and may be fatally harmed if exposed to such temperatures.

However, the use of relatively high temperatures in assembling certain of the mount parts is unavoidable. Such high temperatures are required, for example, for fixing the lead-in members on which the end plates are mounted to walls defining an opening in the header. Where such header is made of a ceramic such as aluminum oxide, the fixing operation involves heating the header and lead-in members to a temperature sufficiently high to fuse a metal coating on the aforementioned walls into fixed engagement with the lead-in members. The heating operation is usually performed in an oven, as a consequence of which the end plates supporting the cathode and in turn supported by the lead-in members, are also heated to the high temperature referred to. Such high temperature would have seriously harmed the cathode if it had been fixed to the end plates engaging the lead-ins prior to this heating operation.

The high temperatures referred to have also been required when fixing the grid side rods to walls of openings through a ceramic header. Such fixing has also involved subjecting the header and grid to oven treatment. The problem of protecting a previously mounted cathode from excessive temperatures during this treatment is particularly serious, since practical manufacturing procedures require that the cathode be mounted prior to the mounting of the grid. The reason for this requirement is that once the grid is mounted, it shields the cathode to such extent as to render a subsequent mounting of the cathode difficult if not impossible, from a practical standpoint.

Accordingly, it is an object of the present invention to provide a mount having parts fixed by heat treatments and having a directly heated oxide coated cathode free from harm by said heat treatments.

A further object is to provide an electron tube mount having a ceramic header and a cathode support structure fixed to said header by a relatively high temperature treatment without harm to said cathode.

Another object is to provide an electron tube mount

2

comprising a tubular directly heated oxide coated cathode and a tubular grid around the cathode mounted on a common ceramic header, with said cathode preserved from harm during the latter application of relatively high temperatures for fixing the grid to the header.

A further object is to provide a novel support for a grid to allow the mounting of an oxide coated cathode on one face of a flat insulating header and the fixing of the grid to said header at a region spaced from the opposite face of said header, whereby the cathode is free from harm by the heat used in fixing the grid.

Another object is to provide a method of assembling the parts of an electron tube mount having an oxide coated cathode, in a sequence to preserve said cathode from harm by relatively high temperatures used in the assembling operation.

A further object is to provide a method of assembling the parts of an electron tube mount comprising fixing at least one of said parts to a flat insulating header in a region disposed to one side of said header, and fixing another of said parts to said header in a region appreciably spaced from the other side of the header to preserve said first named part from heat used in fixing the second named part.

According to a structural feature of the invention, a mount sub-assembly including a flat header of insulating material, is provided with a cathode support structure extending from one face of the header and a grid support in the form of a sleeve extending from the other face of the header and providing a region remote from the cathode support for fixing a grid to the sleeve. In this way it becomes possible to mount a cathode on the support prior to the mounting of the grid on the header, since the region in which the grid is fixed is remote from the cathode.

According to a method aspect of the invention, an oxide coated cathode is mounted in a position disposed to one side of a flat insulating header and a grid is thereafter mounted on the header and surrounds the cathode and is fixed to the header by a support at a region spaced from the other side of the header, for protecting the cathode from heat used in fixing the grid.

Further objects and features of the invention will become apparent as the description proceeds.

In the accompanying drawing, to which reference is now made for a description of one example of practicing the invention,

FIGURE 1 shows an elevation, partly in section, of an electron tube mount in which the invention is embodied;

FIG. 2 is a bottom view of the mount shown in FIG. 1;

FIG. 3 is a fragmentary sectional view taken along the line 3—3 of FIG. 1;

FIG. 4 is an exploded perspective view of parts constituting a sub-assembly of the mount in accordance with the invention; and

FIG. 5 is an exploded perspective view of a sub-assembly formed by the parts shown in FIG. 4, together with certain other parts required to complete the mount structure shown in FIG. 1.

A more specific reference to the drawing will reveal that the electron tube mount shown in FIG. 1 comprises a header 10, made of an insulating material such as a ceramic, made, for example, of aluminum oxide. On the header 10 are mounted a cathode structure 12 and a grid structure 14.

The cathode structure 12 includes metal end plates 16, 18 to which a directly heated tubular mesh cathode 20 is fixed. The fixed regions include end portions of the cathode of relatively small axial extent thereby assuring a relatively large intermediate and active portion of the cathode. The cathode mesh may comprise nickel wires suitably conditioned for electron emission by an emitting

ELECTRON TUBE MOUNT INCLUDING TWO ELECTRODES SUPPORTED ON A COMMON INSULATING HEADER

Carl Theodore Johnson, New Providence, Pa., assignor to Radio Corporation of America, a corporation of Delaware

Filed Dec. 21, 1960, Ser. No. 77,399
8 Claims. (Cl. 313—260)

The present invention relates to an electron tube mount having a structure for facilitating the assembling of the parts thereof in a predetermined order, and to an advantageous method of assembling the parts referred to.

One type of electron tube includes a mount comprising a header of insulating material on which are mounted in concentric relation a directly heated cathode and a tubular grid having a plurality of side rods supporting a helix of lateral wire. The directly heated cathode may have a tubular structure constituted of a wire mesh, to the end portions of which are affixed metal rings or end plates for connecting the end portions aforementioned to suitable lead-ins.

Certain considerations involved in the aforementioned mount make it critical that the parts thereof be mounted in a desired order. One of the major considerations is related to the cathode. One type of tubular mesh cathode is composed of wires that have been conditioned suitably for emission, prior to the assembly thereof in the mount. Such conditioning may involve coating the wire with emitting material. The coating so produced is sensitive to relatively high temperatures prior to enclosure of the cathode in an evacuated envelope, and may be fatally harmed if exposed to such temperatures.

However, the use of relatively high temperatures in assembling certain of the mount parts is unavoidable. Such high temperatures are required, for example, for fixing the lead-in members on which the end plates are mounted to walls defining an opening in the header. Where such header is made of a ceramic such as aluminum oxide, the fixing operation involves heating the header and lead-in members to a temperature sufficiently high to fuse a metal coating on the aforementioned walls into fixed engagement with the lead-in members. The heating operation is usually performed in an oven, as a consequence of which the end plates supporting the cathode and in turn supported by the lead-in members, are also heated to the high temperature referred to. Such high temperature would have seriously harmed the cathode if it had been fixed to the end plates engaging the lead-ins prior to this heating operation.

The high temperatures referred to have also been required when fixing the grid side rods to walls of openings through a ceramic header. Such fixing has also involved subjecting the header and grid to oven treatment. The problem of protecting a previously mounted cathode from excessive temperatures during this treatment is particularly serious, since practical manufacturing procedures require that the cathode be mounted prior to the mounting of the grid. The reason for this requirement is that once the grid is mounted, it shields the cathode to such extent as to render a subsequent mounting of the cathode difficult if not impossible, from a practical standpoint.

Accordingly, it is an object of the present invention to provide a mount having parts fixed by heat treatments and having a directly heated oxide coated cathode free from harm by said heat treatments.

A further object is to provide an electron tube mount having a ceramic header and a cathode support structure fixed to said header by a relatively high temperature treatment without harm to said cathode.

Another object is to provide an electron tube mount

comprising a tubular directly heated oxide coated cathode and a tubular grid around the cathode mounted on a common ceramic header, with said cathode preserved from harm during the latter application of relatively high temperatures for fixing the grid to the header.

A further object is to provide a novel support for a grid to allow the mounting of an oxide coated cathode on one face of a flat insulating header and the fixing of the grid to said header at a region spaced from the opposite face of said header, whereby the cathode is free from harm by the heat used in fixing the grid.

Another object is to provide a method of assembling the parts of an electron tube mount having an oxide coated cathode, in a sequence to preserve said cathode from harm by relatively high temperatures used in the assembling operation.

A further object is to provide a method of assembling the parts of an electron tube mount comprising fixing at least one of said parts to a flat insulating header in a region disposed to one side of said header, and fixing another of said parts to said header in a region appreciably spaced from the other side of the header to preserve said first named part from heat used in fixing the second named part.

According to a structural feature of the invention, a mount sub-assembly including a flat header of insulating material, is provided with a cathode support structure extending from one face of the header and a grid support in the form of a sleeve extending from the other face of the header and providing a region remote from the cathode support for fixing a grid to the sleeve. In this way it becomes possible to mount a cathode on the support prior to the mounting of the grid on the header, since the region in which the grid is fixed is remote from the cathode.

According to a method aspect of the invention, an oxide coated cathode is mounted in a position disposed to one side of a flat insulating header and a grid is thereafter mounted on the header and surrounds the cathode and is fixed to the header by a support at a region spaced from the other side of the header, for protecting the cathode from heat used in fixing the grid.

Further objects and features of the invention will become apparent as the description proceeds.

In the accompanying drawing, to which reference is now made for a description of one example of practicing the invention,

FIGURE 1 shows an elevation, partly in section, of an electron tube mount in which the invention is embodied;

FIG. 2 is a bottom view of the mount shown in FIG. 1;

FIG. 3 is a fragmentary sectional view taken along the line 3—3 of FIG. 1;

FIG. 4 is an exploded perspective view of parts constituting a sub-assembly of the mount in accordance with the invention; and

FIG. 5 is an exploded perspective view of a sub-assembly formed by the parts shown in FIG. 4, together with certain other parts required to complete the mount structure shown in FIG. 1.

A more specific reference to the drawing will reveal that the electron tube mount shown in FIG. 1 comprises a header 10, made of an insulating material such as a ceramic, made, for example, of aluminum oxide. On the header 10 are mounted a cathode structure 12 and a grid structure 14.

The cathode structure 12 includes metal end plates 16, 18 to which a directly heated tubular mesh cathode 20 is fixed. The fixed regions include end portions of the cathode of relatively small axial extent thereby assuring a relatively large intermediate and active portion of the cathode. The cathode mesh may comprise nickel wires suitably conditioned for electron emission by an emitting

coating thereon, such as barium carbonate. The metal end plates 16, 18, may, for example be made of nickel. Metal end plate 16 is supported on a metal lead member 22 which may be made of an alloy known commercially as Kovar and containing iron, nickel and cobalt. The lead member 22 is sealed through the header 10 in a vacuum tight bond. Lead member 22 passes through an insulating sleeve 24 in the end plate 18, as shown in FIG. 3, to provide electrical insulation between end plates 16, 18. End plate 18 is fixed to a lead member 26, which also may be made of Kovar and which is sealed through the header 10 in a vacuum tight manner. In a completed electron tube, connection of lead member 26 and the exposed prong portion 28 of the lead member 22, across a suitable power supply (not shown) will cause current to flow through the cathode 20 to thereby raise it to emitting temperature.

The cathode 20 may be fixed to the end plates 16, 18 in one of several ways, including brazing, welding or by the application of a molten metal spray. Each of these ways of fixing requires access to the end portions of the cathode from radial directions.

The grid structure 14 comprises a plurality, in the instant example six, side rods 30 to 40, as shown fully in FIG. 3. The side rods may be made of molybdenum and may have a thickness of .040 inch. Around the side rod array is disposed a helix 42 of grid lateral wire which may be made of molybdenum and have a thickness of about 0.010 inch. The helix is suitably fixed to the side rods, as by being brazed thereto, for example. The helix has an axial dimension substantially equal to that of the cathode 20 and overlaps the end portions of the cathode at which the cathode is fixed to the end plates 16, 18. The grid, therefore, precludes accessibility to the regions wherein the cathode is fixed to the end plates referred to, from directions radially of the end plates and cathode.

A metal ring 44 is sealed to the periphery of the header 10 in a vacuum tight fashion, and has a flange 46 to which a metal envelope or anode (not shown) may be sealed for completion of an electron tube.

According to one feature of the invention, the grid 14, and the header 10 are characterized by structure to permit a mounting of the grid on the header, subsequent to the fixing of the cathode 20 to the end plates 16, 18 and without harm to the cathode. To this end, the header 10 includes metal sleeves 48, 50, 52 (FIG. 2) made for example, of Kovar, an alloy previously described. The sleeves are sealed to walls defining openings through the header 10, in a vacuum tight manner. The metal sleeves are so arrayed about the axis of header 10, as to be in register with alternate ones of the side rods, for a purpose to be explained. Thus side rods 30, 34, and 38 are in register with and extend through the sleeves 48, 50, 52 respectively. Preferably, the side rods referred to extend slightly beyond the lower free ends of the sleeves as shown in FIG. 1 for rod 30 and sleeve 48. This provides an annular region for accommodating a body of solder 54. The solder or brazing material may be a composition known commercially as Nioro, and which includes nickel and gold. While this is a relatively high temperature solder (i.e. 900° C.) its disposition in the annular region referred to is sufficiently remote from the cathode 20, so that the latter is not harmed by the temperature used. The solder engages the free ends of the sleeves 48, 50, 52 and the sides of the end portions of the side rods 30, 34, 38 threaded therethrough, in rugged bonds. The bonding region aforementioned may be spaced about one-half inch from the adjacent face of header 10, to assure the desired space isolation of this region from the cathode 20.

According to a method feature of the invention, the assembling of the parts forming the cathode mount shown in FIG. 1, is accomplished in two steps. The first step involves assembling in fixed relation, the parts shown in FIG. 4, to provide a subassembly of the mount. In the

second step the parts shown in FIG. 5 are fixed in assembled relation. One of the parts employed in the second step, is the sub-assembly aforementioned.

The parts assembled in the first step comprises a cathode support structure 56, the metal sealing ring 44, the ceramic header 10, and the three sleeves 48, 50 and 52, shown in FIG. 4. To facilitate the assembling of these parts the periphery of header 10, as well as the walls defining openings 53, 60, 62, 64 and 66 are suitably provided with a coating of molybdenum. The coating of molybdenum may be in turn covered by a relatively thin layer of a metal such as copper or metal, to facilitate a wetting of the parts extended into the openings and the part engaging the periphery of the header 10, for promoting good seals.

The assembling of the parts shown in FIG. 4 may be aided by a suitable jig (not shown). Thus with the header 10 supported on the jig, the ring 44 may be telescoped over the header so as to engage the periphery thereof, the prongs 26, 28 of the cathode support structure 22 may be extended through openings 62, 66 of the header until the end plate 18 rests on the upper surface of the header, and the sleeves 48, 50, 52 may be extended into openings 53, 60, 64 so as to be flush with or extend slightly above the upper surface of the header as shown in FIGS. 4 and 5, and to extend below the lower surface a distance of about one-half inch. In the example, the header 10 had a diameter of one and one-half inches, and the downwardly extending portions of the sleeves 48, 50, 52 had a length of one-half inch. When assembled as indicated, the parts are in snug engagement and separated only by the coating or coatings before described. The assembled relation is preserved, not only by the snug engagement referred to, but by the jig (not shown) on which the parts are assembled and on which they rest.

The jig with the parts thus assembled thereon and supported thereby, is then placed in an oven and subjected to a temperature of 820° C. for seven minutes. At this temperature, the outer coatings on the walls of the openings and on the periphery of the header 10 become fused, and bond effectively to the sleeves 48, 50, 52 and the prongs 26, 28 of the cathode support structures, as well as to the sealing ring 44. After cooling, the jig and the sub-assembly thereon, which has now become integrated, are removed from the oven. The sub-assembly is then removed from the jig and constitutes a sub-assembly 67 which is one of the parts dealt with in the second step of the method under consideration, as shown in FIG. 5.

Besides the sub-assembly 67, the second step of the method affects the grid structure 14 and the tubular mesh type cathode 20. In carrying out the second step, the mesh cathode 20 is first telescoped over the end plates 16, 18 of the cathode support structure 67, so that end portions of the cathode engage the peripheries of the end plates referred to. The tubular cathode 20 has an inner diameter of .625 inch which is substantially equal to the diameter of each of end plates 16, 18 so that after the telescoping operation, the cathode engages the end plates snugly. While so snugly engaged, the engaged end portions of the cathode are fixed to the end plates in a suitable manner. One way in which this may be accomplished is by spraying a molten metal such as molybdenum over the end portions of the cathode so as to at least partly fill interstices formed by the wires of the cathode. This at least partial filling of the interstices bonds the end portions of the cathode to the peripheries of the end plates 16, 18.

After the cathode is fixed to the cathode support structure as described, the grid structure 14 is telescoped over the cathode and oriented so that the longer side rods 30, 34, 38 of the grid are in axial register with sleeves 48, 50, 52 and enter the sleeves. When in fully telescoped position, the shorter side rods 32, 36, 40 of the grid have their lower ends, as viewed in FIG. 5, in abutment with

the upper surface of the header 10. Such abutment desirably orients the grid axially in the electrode mount shown in FIG. 1. The length of the longer side rods 30, 34, 38 is such that when the foregoing abutment occurs, the longer side rods 30, 34, 38, extend slightly below the lower ends of the sleeves 48, 50, 52 as shown in FIG. 1, to permit convenient solder bonding of the lower end portions of the sleeves and the longer side rods referred to. The sleeves 48, 50, 52 have an inner diameter for snugly engaging the longer side rods aforementioned and an outer diameter for being engaged snugly in openings 53, 60 and 64 in the header 10.

It will be noted from the foregoing that the lower end portions of the sleeves 48, 50, 52 and the longer side rods 30, 34, 38 are appreciably spaced from the header 10 and the cathode 20. Furthermore, the solder 54 is applied by localized heat, such, for example, as by dipping the lower end portions of the sleeves and longer side rods into a pot of molten solder. A better way of applying the solder, from the standpoint of the amount of heat produced at the regions to be soldered, is to heat the end portion of each sleeve individually to soften the solder composition previously deposited thereon, the heating being accomplished by a radio-frequency coil connected to a suitable power source and having a diameter for heating only one sleeve end portion. A plurality of coils of this type may be used, to provide one coil for each sleeve, so as to solder simultaneously the three sleeves to their associated grid side rods. However, it is preferred to employ only one coil, and to successively heat the three sleeve ends to the melting point of the solder. In this way the quantity of heat used at any one period of time, is reduced to a minimum and provides maximum assurance against heat damage to the cathode. This assurance against heat damage to the cathode is also contributed to by the relatively low heat conductivity characteristic of the Kovar alloy of which the sleeves are composed.

The spacing of the end portions aforementioned of the sleeves and longer side rods from the header 10, and the localized character of the heat used in fixing the longer side rods to the sleeves, preserves the emission-conditioned cathode from harm during the fixing operation.

While the provision of side rods of different length is utilized in the previously described example for properly localizing the lower end portions of the longer side rods for conveniently fixing such end portions to the sleeves described, this difference in side rods length is also of advantage in mounting two concentric grids in such a way that the laterals thereof are in alignment transversely of the grid axis. This result can be achieved by cutting the shorter side rod legs in the several grids so that the lengths thereof beyond the final turn of grid lateral wire are equal. In this way, the shorter side rods constitute reference means for desirable alignment of the turns of the several grids, and a fixing of the grids may be accomplished solely by the longer grid side rods.

While the aforescribed method provides for assembling the cathode 20 in the mount after the sub-assembly 66 (FIG. 5) has been fixed by oven heating, this order in the assembling operation is dictated by the fact that, in the example described, the cathode was coated with emitting material prior to the mounting of the cathode on the sub-assembly 67. Such prior application of the coating made it necessary to keep the cathode away from excessive heat, such as that involved in oven heating the sub-assembly 67.

However, it is feasible, according to the invention to defer application of the emitting coating to the cathode 20, until after the cathode is assembled in sub-assembly 67. This permits the sub-assembly 67, with the uncoated cathode 20 loosely mounted thereon, to be oven-heated without damage to the cathode. Besides fixing the elements of sub-assembly 67 (FIG. 5) the oven heating may also be utilized for fixing the uncoated cathode 20 to

the end plates 16, 18 of the sub-assembly. This may be done by precoating the peripheries of the end plates with a suitable brazing material having a fusion point at the temperature of the oven. After the uncoated cathode 20 is thus fixed to the sub-assembly, the cathode may be suitably coated with emitting material as aforementioned. An advantage of this modified method resides in the fact that the fixing of the elements of the sub-assembly 67, as well as the cathode 20 may be effected in a single heating operation.

It is, of course, necessary in either way of mounting the cathode 20, to defer the mounting of the grid 14 until after the cathode has been fixed to the sub-assembly 67 and suitably coated with emitting material. This is for the reason that the grid, when positioned around the cathode, obstructs access to the cathode required for application of the emitting coating.

What is claimed is:

1. An electron tube mount comprising a tubular electrode having at least two support rods, a header made of insulating material and having a metal sleeve extending therethrough and beyond one face thereof for service as a contact prong, said electrode extending from the other face of said header, one of said support rods abutting against said other face of the header, said one of said support rods being free to move laterally of said header, the other of said rods extending through said sleeve, and means fixing said other of said rods to an end portion only of said sleeve remote from said header, said sleeve constituting the sole support means for said at least two support rods against lateral movement with respect to said header.

2. An electron tube mount according to claim 1 and wherein said means for fixing comprises solder engaging the end of said sleeve extending from said one face of the header and the free end portion of said other of said rods.

3. An electron tube mount comprising a tubular cathode, a tubular grid in concentric relation to said cathode, an insulating header, means engaging said header and supporting said cathode to one side of said header, said grid having a first side rod, a metal sleeve forming a vacuum tight seal with and extending through said header and including a portion extending away from the other side of said header, said first side rod extending through said sleeve, said grid having a second side rod in end butt relation to said one side of said header, said first and second rods having lengths to cause said first rod to extend beyond the free end of said portion of the sleeve when said second rod abuts against said one side of the header, and means engaging the extending portion of said first rod and said free end of said sleeve for fixing said grid to said header, said sleeve constituting the sole support means for said first and second side rods against lateral movement with respect to said header.

4. An electron tube mount comprising an insulating header having opposite faces, a cathode support extending from one face of said header, a cathode fixed to said support only in regions spaced from said one face, a tubular grid support sealed vacuum tight to and extending from the other face of said header, and a grid having a side rod extending through and fixed to said grid support only in regions spaced from said other face, said cathode and grid being in concentric relation, said grid having another side rod, said tubular grid support constituting the sole support means for said first named side rod and said another side rod against lateral movement with respect to said header.

5. An electron tube mount according to claim 4 and wherein said grid includes two side rods of different length and wherein the shorter of said side rods has an end in abutment with said one face of said header for fixing the adjacent end of the longer side rod in a position remote from said other face of said header.

6. A grid mount for an electron tube comprising:

- (A) a tubular grid having a plurality of parallel side rods,
- (B) a plurality of grid wires extending transversely of and fixed to said side rods and forming an array terminating in a plane normal to said side rods,
  - (1) said side rods including end portions extending from said plane in a direction remote from said array,
  - (2) alternate ones of said end portions being of equal length, the others of said end portions being of equal length and longer than said alternate ones of the side rods,
- (C) a flat insulating envelope header having openings extending therethrough,
- (D) metallic sleeves hermetically sealed through said openings,
  - (1) said sleeves extending farther from one face of said header than from the opposite face thereof,
  - (2) said others of said end portions extending through said sleeves and beyond the end thereof extending from said one face of the header,
  - (3) said alternate ones of the end portions abutting against the other face of said header,
  - (4) said other end portions being fixed only to 25 said end of the sleeve,
  - (5) said sleeves constituting the sole means for supporting said grid against lateral movement with respect to said header.

7. A cathode-grid mount for an electron tube comprising:

- (A) a flat insulating envelope header,
- (B) a tubular cathode having a coating of an emitting carbonate thereon, and fixed to and extending from one face of said header,
- (C) a tubular grid positioned in concentric relation to said cathode and having a plurality of parallel side rods, said grid having an effective area terminating in a plane normal to said side rods,
  - (1) alternate ones of said side rods including 40 portions extending from said plane and away from said effective area,
- (D) conductive sleeves hermetically sealed through said header and extending from the other face of the header,
  - (1) the others of said side rods being in end abutment with respect to said one face of the header,
  - (2) said portions of said alternate side rods extending through and being longer than said sleeves to cause end regions of said rod portions to protrude from the ends of said sleeves remote from said other face of the header,
  - (E) and fixing means engaging said protruding end

- regions of said alternate side rods and said ends of the sleeves, whereby said fixing means is spaced from said cathode to preserve the coating thereon from harm by heat required to form the fixing means,
- (F) said sleeves constituting the sole means for supporting said grid against lateral movement with respect to said header.

8. An electron tube mount comprising:

- (A) an insulating header adapted to form a wall portion of an electron tube envelope,
- (B) a tubular grid mounted on one face of said header,
- (C) an additional electrode mounted on said one face and closely spaced with respect to said grid, said electrode being made of a material that undergoes undesired chemical change when heated to a predetermined temperature,
- (D) said grid including a plurality of side rods having one group of adjacent ends thereof terminating in a plane normal to the side rods,
  - (1) said side rods having a second group of ends opposite to the first group of ends,
  - (2) a first of said side rods having an end in said second group in abutment against said one face of the header,
- (E) at least one metal sleeve hermetically sealed through said header and including a major portion extending perpendicularly from the other face of said header,
  - (1) and at least another of said side rods having a longer length than said first side rod and extending into said at least one sleeve to a region thereof adjacent to the free end of said major portion of the sleeve,
  - (2) said at least another side rod being joined to said region in a bond formed at said predetermined temperature,
  - (3) said at least one metal sleeve being the sole support of said grid against lateral movement with respect to said header.
